United States Patent Office

Des. 190,782
Patented June 27, 1961

190,782

GRAVE MARKER

Vincent F. Tartaglia, 2409 Lancaster Ave.,
Wilmington, Del.

Filed May 10, 1960, Ser. No. 60,529

Term of patent 14 years

(Cl. D79—2)

FIG. 1.

FIG. 2.

FIG. 3.

FIG. 1 is a plan view of a grave marker, showing my new design;

FIG. 2 is a side elevation thereof; and

FIG. 3 is an end elevation thereof.

The dominant features of my design reside in the portions shown in full lines.

I claim:

The ornamental design for a grave marker, as shown and described.
